UNITED STATES PATENT OFFICE.

WILLIAM J. KERWIN, JR., OF SOUTH DARTMOUTH, MASSACHUSETTS.

METHOD OF MANUFACTURING COLORED YARNS.

Application filed March 31, 1927. Serial No. 180,005.

This invention relates to a method of, and apparatus for, manufacturing colored yarns to produce various shaded or ombre effects, or various colored tints and hues therein.

5 In my Patent No. 1,572,148, granted February 9, 1926, one method of producing the desired color effects is disclosed. Generally stated, that process consists in cutting sections from differently colored or shaded laps 10 of fibrous material and disposing these sections on the moving apron of a card or like machine in a definite order so that the yarn produced, though greatly attenuated, will have the desired shading due to this arrangement. These laps are sheets of fibrous material of uniform width and generally uniform thickness and are wound into rolls of 15 convenient size. The sections, some of which are triangular, are cut from these laps by a pattern laid upon them. The sections when disposed on the apron constitute a strip of uniform width. In this strip triangular, or triangular and rectangular sections of different colors or shades are placed adjacent each 20 other so that in the yarn produced there will be a uniformly graduated shading or blending from one color or shade to the other.

The commercial application of this patented method, while producing the desired 30 results, involves a considerable amount of waste in material and a certain amount of excess labor which it is an object of the present invention to avoid. The saving in labor realized by the present proposed method will 35 be understood when the new method is explained in detail hereinafter; the saving in material will be better understood from an explanation of the sources of waste according 40 to the former method. This explanation of some of the sources of waste follows:

First, the lap from which the sections are cut while of generally uniform thickness over its entire length, is not of uniform thickness at every point in its length. Thus, 45 there may be thin portions followed by thicker portions. In forming the lap on the card apron according to the patented invention, if too thick or thin portions occur they must be discarded and thrown back to the 50 previous machine. The lap on the apron must be of uniform thickness when the apron moves at a given linear velocity to feed the material to the card, in order to produce a sliver of uniform weight throughout its 55 length.

Second, cutting out of the thick or thin

sections involves the loss of a certain length of the lap on at least one side of the cut if the length of the lap from the section last removed to the cut is shorter than the shortest pattern section employed.

Third, the end portions of the lap in a roll are usually irregular and since the pattern has straight sides, the ragged ends of the lap are wasted.

Fourth, the material in the lap is not well matted and frequently tears, or pulls apart transversely, and pieces break and fall off the edge. The sections of the lap at these points have to be cut out. This mutilation of the lap occurs both during the handling while cutting the sections and also when the rolls are stored for use, as they must be to some extent, to keep the card running should the machines producing the laps be temporarily disabled or be producing some other color or shade of lap.

Besides the elimination of waste in labor and material, the present invention has for an object the production of different sizes of yarn of the same type without a change of the apparatus employed.

Other objects will be apparent from the following description and accompanying illustration, in which:

Figure 1 is a side elevation of "breaker" and "finisher" carding machines of conventional type arranged in tandem and fitted for use with my improved method;

Figure 2 is a diagrammatic plan view of the top section of the enlarged feeding apron showing certain patterns or sections formed thereon; and

Figure 3 is a view similar to Fig. 2 but showing an additional superimposed pattern formed in outline over the first, for employment in making yarn of larger diameter.

Referring to Fig. 1 of the drawings, 12 designates a breaker card of usual type, and 13 a finisher card arranged in tandem therewith. Between the two cards is a cross feeding mechanism 14, commonly called a scotch feeder, for transferring the sliver from the breaker to the finisher, and at the doffer end of the finisher is a condenser 15. These several units of machinery may be of any suitable construction, the cards being preferably of the full roller type as designated for operation under what is termed the cotton waste or woolen system.

In adapting the above described machines to the purpose of the present invention, it is only

necessary to make a slight change in the construction of the breaker card. This alteration consists in extending the feed table 16 to several times its usual length whereby 5 more surface is afforded for apportioning and laying out the different colored or shaded sections of fibrous material on the feed apron or conveyor 17. The conveyor is an endless belt type, preferably of the lattice type, moving toward the card on its top surface, and any well known means is provided for changing the linear speed of the conveyor relative to the speed of the card.

The scotch feeder 14 comprises means for 15 delivering the slivers from the doffer 18 of the breaker card 12 to an elevated conveyor 19 which transfers it to a traversing carriage 20 acting to lay it at the back of the finisher card 13.

The condenser 15 employed with the finisher card may be of any suitable type, a tape condenser being illustrated as the present preferred form. The function of this unit is to divide the web from the finisher card doffer into strips which are carried along by 25 tapes to the condenser rolls and rubbed into strands of roving, issuing in a large number of ends which are wound upon jack spools 22. From the condenser 15 the roving is 30 transferred to the spinning machines to be spun into yarn. For the spinning process I may employ ring spinning frames or mules, but as such machines are well known in the art and have no particular function related to 35 the present method of manufacture, it is unnecessary to illustrate or describe the same in the present application.

A preferred arrangement of machinery for use with my improved method of manufacture having been above described, the 40 method of carrying out the steps of the process will be explained. The feature of the process described in the patent referred to, consists in using sections of variously colored or shaded fibrous material in layers or sheets of uniform thickness, and combining sections of two or more laps of different shades or colors to cause one shade to gradually merge into another in the roving, or 45 one color to shade into another tint; or by combining complementary colors to produce entirely different tints or hues and variegated effects in the roving and finally in the yarn. Any number of differently colored or shaded 50 fibers may be employed and these may be combined in varying proportions but it will be sufficient for an understanding of the present invention to explain the simplest method with the use of fibers dyed in two contrasting colors or shades combined in equal parts.

According to the process of the patent, the lap on the apron of the card is formed from pieces cut to exact shape from a web or lap 55 of fibers of uniform width and thickness,

and waste results, as pointed out. According to the present invention this is eliminated by taking pieces of material of any shape or size and building up the sections on the apron. Indeed the stock may be in 70 bunches or handfuls taken directly from a vertical opener, or from the front of the picker, in bulk, without allowing the lap to form.

In order that the operator shall build up 75 the sections of proper sizes and shapes, a pattern is marked on the apron 17. This pattern may be composed of sections of any desired configuration but the form illustrated 80 consists of rectangles and triangles, the triangles of one color or shade being arranged upon either side of a rectangle of the same color to form parallelograms or rhomboids tapering towards their ends. Such a configuration is indicated in Figure 2 and consists of the rectangle B and the triangles C, C. An adjoining configuration of a second color or shade is composed of the rectangle E and the triangles D, D. The sections of alternate colors are thus continued 85 in successive alternation about the entire length of the conveyor. Preferably, the sections are painted upon the surface of the conveyor.

A quantity of fibrous material of one color or shade is spread out over one of the sections, say C, B, C. The quantity may consist of irregular pieces or batches. A like quantity of material of another color or shade is spread out to a uniform thickness 90 on the adjacent section D, E, D and so on. Should the material come in sheets of regular thickness but irregular sizes, the sheets are laid upon the marked sections and their edges pushed into contact. If necessary or 95 desirable the sheets may be cut or pulled apart by hand to cause them to fit together without leaving open spaces and also to confine the material within the enclosing lines of the sections. Alternatively a weighed 100 amount of loose material in batches of indiscriminate shape and size may be spread by hand over the sections. It has been found that a moderately skilled worker can distribute the material quite evenly when gauging the thickness by sight and feel. Even if the material is spread so as to have small 105 lumped areas, the average diameter of the rovings will not be affected to any extent so long as the thick or thin areas do not extend completely across the apron. Usually the 110 thick and thin spots by this method of laying on the material offset each other.

The conveyor 17 is of the type which is 115 adapted to be operated at different speeds to vary the size of roving produced, it being apparent that the faster the conveyor travels the more material will be fed to the card within a given time and the heavier each strand of roving. Assuming the thick- 120 125 130

ness of material spread on the apron to remain constant, it will be necessary to have an elongated pattern capable of holding more material if the shading of the yarn is 5 to be kept uniform over a given length, when the conveyor speed is increased. In Figure 3 there is shown such an elongated pattern painted in outline in two contrasting colors over the primary pattern already 10 described. The superimposed pattern is similar in every way to the first. It consists of rectangles B' and triangles C', C' of one color, and triangles D', D' and rectangles E' of a second color arranged as before 15 in alternating rhomboids or parallelograms of such length and number as to occupy in an even number the entire length of the belt conveyor. By forming two or more patterns in superimposed fashion, the 20 same conveyor used for slow feed and light yarns may be made to serve without change for rapid feed and heavier yarn.

The operation of machines to produce the desired type of yarn and the manner in 25 which such yarn is knitted or woven to bring out the desired color effect in the fabric are completely described in my patent and well understood by those skilled in this art and need not be recounted here, since 30 the present method as to those steps is the same as the method set forth in the patent.

It is to be understood that the invention is not limited to the exact details set forth, but includes modifications and changes coming 35 within the scope of the appended claims.

The term colors as used in the claims is intended to cover the primary colors and combinations of such colors.

Having thus described the invention, 40 what is claimed as new and desired to be secured by Letters Patent is:

1. A feed conveyor for fiber parallelizing apparatus comprising an endless belt having a pattern provided upon its surface, said 45 pattern consisting of a plurality of sections alternately arranged progressively along the length of the conveyor.

2. A feed conveyor for fiber parallelizing apparatus comprising an endless belt having a pattern provided upon its surface, said 50 pattern consisting of a plurality of contrastingly colored sections arranged in alternate relation progressively along the length of the conveyor.

3. A feed conveyor for fiber parallelizing apparatus comprising an endless belt having a plurality of patterns provided upon its surface for selective utilization, each of said 55 patterns consisting of a plurality of sections alternately arranged progressively along the length of the conveyor.

4. A feed conveyor for fiber parallelizing apparatus comprising an endless belt having a plurality of patterns provided upon its 60 surface for selective utilization, each of said 65

patterns consisting of a plurality of contrastingly colored sections arranged in alternate relation progressively along the length of the conveyor.

5. A feed conveyor for fiber parallelizing 70 apparatus comprising an endless belt having a plurality of separately distinctive patterns provided upon its surface for selective utilization, one of said patterns consisting of a plurality of contiguous sections in contrast- 75 ing solid colors arranged in alternate relation progressively along the length of the conveyor and another of said patterns consisting of a plurality of contiguous sections indicated in outline over the first pattern in 80 alternate relation progressively along the length of the conveyor.

6. A feed conveyor for fiber parallelizing apparatus comprising an endless belt having a pattern provided upon its surface, said 85 pattern consisting of a plurality of tapering sections alternately arranged progressively along the length of the conveyor.

7. A feed conveyor for fiber parallelizing apparatus comprising an endless belt hav- 90 ing a plurality of separately distinctive patterns provided upon its surface for selective utilization, one of said patterns consisting of a plurality of contiguous tapering sections in contrasting solid colors arranged in 95 alternate relation progressively along the length of the conveyor and another of said patterns consisting of a plurality of contiguous tapering sections indicated in out- 100 line over the first pattern in alternate relation progressively along the length of the conveyor.

8. A feed conveyor for fiber parallelizing apparatus comprising an endless belt hav- 105 ing a plurality of separately distinctive pat- terns provided upon its surface for selective utilization, each of said patterns consisting of a plurality of contiguous mutually dis- 110 tinctive tapering sections arranged in alternate relation progressively along the length of the conveyor, said patterns having sections of several lengths respectively adapting the patterns for utilization when the feed conveyor speed is changed to produce a different weight of stock. 115

9. In a method of manufacturing colored yarns, the steps consisting in providing an elongated pattern comprising a plurality of distinctive adjacent sections of definite configuration disposed in alternate relation pro- 120 gressively along the length of a feeding apron and filling in each section to a uniform depth with portions of fibrous material from bulk of different colors, each section being filled with a material of a color dif- 125 ferent from that of an adjacent section.

10. In a method of manufacturing colored yarns, the steps consisting in providing an elongated pattern comprising a plurality of tapering sections disposed in alternate rela- 130

- tion progressively along the length of a feeding apron and filling in each section to a uniform depth with portions of fibrous material from bulk of different colors, each section being filled with a material of a color different from that of an adjacent section.
11. In the method of manufacturing colored yarns, the steps which comprise taking portions of fibrous material from bulk of different colors, and spreading the portions in sections of desired outlines upon a forming surface, each section being made up of fibrous material of the same color.
12. In the method of manufacturing colored yarns, the steps which comprise taking portions of fibrous material from bulk of different colors, and spreading the portions in sections of desired outlines upon a forming surface, the said sections being disposed in alternate relation progressively along the length of said forming surface, each section being made up of fibrous material of the same color.
13. In the method of manufacturing colored yarns, the steps which comprise taking portions of fibrous material from bulk of different colors, weighing the said portions, and spreading the weighed portions in sections of desired outlines upon a forming surface, each section being made up of fibrous material of the same color.
14. In the method of manufacturing colored yarns, the steps which comprise taking portions of fibrous material from bulk of different colors, weighing the said portions, and spreading the weighed portions in sections of desired outlines upon a forming surface, the said sections being disposed in alternate relation progressively along the length of said forming surface, each section being made up of fibrous material of the same color.
15. In the method of manufacturing colored yarns, the steps which comprise taking portions of fibrous material from bulk of different colors, and spreading the portions in tapering sections of desired outlines upon a forming surface, each section being made up of fibrous material of the same color.
16. In the method of manufacturing colored yarns, the steps which comprise taking portions of fibrous material from bulk of different colors, and spreading the portions in tapering sections of desired outlines upon a forming surface, the said sections being disposed in alternate relation progressively along the length of said forming surface, each section being made up of fibrous material of the same color. 55
17. In the method of manufacturing colored yarns, the steps which comprise providing a surface having a pattern thereon, and spreading portions of fibrous material taken from bulk of different colors in sections upon said pattern, each section being made up of fibrous material of the same color. 60
18. In the method of manufacturing colored yarns, the steps which comprise providing a surface having a pattern thereon, and spreading portions of fibrous material taken from bulk of different colors in sections upon said pattern, the said sections being disposed in alternate relation progressively along the length of said forming surface, each section being made up of fibrous material of the same color. 65
19. In the method of manufacturing colored yarns, the steps which comprise taking portions of fibrous material from bulk of different colors, and spreading the portions of fibrous material taken from bulk of different colors in tapering sections upon said pattern, each section being made up of fibrous material of the same color. 70
20. In the method of manufacturing colored yarns, the steps which comprise taking portions of fibrous material from bulk of different colors, and spreading the portions of fibrous material taken from bulk of different colors in tapering sections upon said pattern, the said sections being disposed in alternate relation progressively along the length of said forming surface, each section being made up of fibrous material of the same color. 75
